UNITED STATES PATENT OFFICE.

JOHN L. PASCAL, OF POCOHONTAS, IOWA.

ROAD-DRAG.

1,247,999.

Specification of Letters Patent. Patented Nov. 27, 1917.

Application filed March 6, 1917. Serial No. 152,518.

To all whom it may concern:

Be it known, that I, JOHN L. PASCAL, citizen of the United States of America, and resident of Pocahontas, Pocahontas county, Iowa, have invented a new and useful Road-Drag, of which the following is a specification.

The object of this invention is to provide an improved construction for road drags.

0 A further object of this invention is to provide an improved construction for means for leveling and smoothing a traction surface.

A further object of this invention is to 15 provide means for eliminating pockets, hollows and bumps in a traction surface.

A further object of this invention is to provide means for repeatedly treating a given portion of roadway in a single 20 passage of the machine.

A further object of this invention is to provide improved means for adjusting the size and scope of a road drag.

A further object of this invention is to 25 provide an improved sectional construction for a road drag.

A further object of this invention is to provide an improved, flexible construction for a road drag.

30 A further object of this invention is to provide improved means for folding a flexible sectional drag.

A further object of this invention is to provide an improved construction for a 35 smoothing and leveling blade.

My invention consists in the construction, arrangement and combination of elements hereinafter set forth, pointed out in my claims and illustrated by the accompanying 40 drawing, in which—

Figure 1 is a plan of my improved road drag with the derrick devices removed. Fig. 2 is a front end elevation of the complete device. Fig. 3 is a detail section on the 45 line 3—3 of Fig. 1, on an enlarged scale. Fig. 4 is a perspective of the smoothing and leveling blade, on an enlarged scale.

In the construction of the device as shown 50 two main drag sections are employed, and are designated generally by the numerals 10, 11 respectively. Each main drag section 10, 11 is formed of outer sills 12, 13 and inner sills 14, 15 arranged in spaced parallel relations and connected at their forward ends 55 by cross bars 16 and at their rear ends by cross bars 17 rigidly bolted to said sills at

their points of intersection. The sills and cross bars preferably are formed of channel beams arranged with their channels upwardly, and said inner sills 14, 15 are arranged relatively close together and materially closer to each other than to the outer sills 12, 13. Each cross-bar 16, 17 is provided at one end with a hinge member 18 bolted in and projecting from its channel 60 and formed with an eye 19 on its projecting end, and each of said cross bars is formed at its opposite end with registering apertures in the sides of its channel adapted to receive a hinge bolt 20 passing through the eye of a hinge member of an adjacent section, whereby the sections are flexibly connected on longitudinal horizontal axes. Blade-carrying bars 21, 22 are carried by each main drag section 10, 11, each of said 65 bars preferably comprising an angle iron secured at one end to an outer sill 12 or 13 and at its other end to an inner sill 14 or 15 by bolts 23 passing through the bottom of said sills and through the upper and horizontal flange of said angle. On each main drag section 10, 11, two longitudinal rows of bars 21, 22 are provided and said bars 70 are arranged obliquely, at angles of approximately forty-five degrees to the sills and cross-bars of said sections. The foremost blade-carrying bar 21 is connected at its forward end to the innermost sill 13 of the outer sills of the section, relative to the median line of the device, and at its rear end to the adjacent sill 15 of the inner sills 75 of the sections; and the foremost bar of the row 22 is connected at its forward end to the other inner sill 14 and at its rear end to the outermost of the outer sills 12, so that the foremost bars 21, 22 of each section 80 are parallel with each other, but at opposite inclinations to the foremost bars of the other section. The blade-carrying bars 21, 22 of each section are successively inclined in opposite directions in the longitudinal rows in which they are arranged, and the forward end of each of said blades 85 projects slightly beyond the rear end of the next blade forwardly of it. A smoothing 90 and leveling blade 24 of any suitable construction, preferably beveled on its lower margin, is secured to the vertical flange of each blade-carrying bar 21, 22, and a wing 95 25 is secured to the forward end of each of said blades and is bent so as to lie substantially parallel to the sills of the device. The

wings 25 also preferably are beveled rearwardly and downwardly at their forward margins, as shown in Fig. 4. Because of the arrangement of the blade-carrying bars 21, 22, each row of each section presents a succession of blades 24 alternately inclined in opposite directions and adapted for successively working and treating a strip of road surface by dragging loose earth successively 10 in opposite directions and filling in pockets and depressions and cutting off bumps and elevations of such surface, each blade in a given row passing the loose earth rearwardly to the next following blade, which 15 projects therebeyond at its forward end, and with its projecting wing receives such loose earth and the like and passes it rearwardly and laterally and repeated treatment is accorded to the surface in a single passage 20 of the machine. Because of the close arrangement of the inner sills 14, 15, the inner ends of the blade-carrying arms 22 are arranged adjacent the outer end of the arms 21, and the entire surface of the road 25 treated throughout the effective width of the device.

Supplemental side sections 26, 27 may be employed, each of said sections comprising sills 28, 29 and cross bars 30, 31 with blade-carrying bars 32 having blades 24 with projecting wings 25. The foremost blade-carrying bars 32 are connected at their forward ends to the inner sills 28 and inclined rearwardly and connected to the outer sills 29, 35 and the successive blade-carrying bars are successively inclined in opposite directions in a manner similar to that previously described. The supplemental side sections 26, 27 are also provided with hinging devices 40 similar to those previously described, for flexibly connecting said side sections to outer margins of the main sections when desired.

Wing sections 33, 34 also may be provided and employed when desired, each of said 45 sections comprising a sill 35, a forward cross bar 36 projecting laterally therefrom, and a short rear cross bar 37 fixed to the rear end of said sill, said wing sections being adapted for flexible connection to the outer 50 margins of main sections 10, 11 or supplemental side sections 26, 27 as desired. A blade-carrying beam or bar 38 is fixed at one end to the outer end of the forward cross bar 36 of each wing section and inclines 55 rearwardly and inwardly and is fixed at its opposite end to the rear end of the sill 35, or to the short cross bar 37 adjacent said sill; and a second blade-carrying bar 39 is fixed at one end to an intermediate portion 60 of the forward cross bar 36 and is arranged substantially parallel with the bar 38 and fixed at its opposite end to an intermediate portion of the sill 35. The bars 38, 39 may be formed with smoothing and leveling 65 lower margins or may be provided with de-

tachable blades as desired. Thus the wing sections 33, 34 are narrower at their rear ends than at their forward ends, and their blades are arranged in the same direction, on each section and at more gentle inclinations than the blades of the other sections. The entire arrangement of blades is such that the foremost blades 24 of the main and supplemental sections carry loose earth outwardly from the median line of the device 75 and the rearmost blades of such sections carry the residue of loose earth inwardly toward the median line of the device; while the blades of the outermost or wing sections tend to carry loose earth inwardly toward 80 the median line of the device, and also tend to carry inwardly the remains of cut grass and weeds to positions where they will be encountered by traffic and ground to fine portions.

Eyes 41 are fixed to outer ends of the forward cross bars 16 in any suitable manner and clevises 42 engage said eyes and are removably secured to end portions of a draft beam 43. Other clevises 44 are secured to 90 the draft beam 43, conjunctively with the clevises 42 but on the forward side of said beam, and draft chains 45 are secured to said forward clevises and converge forwardly and are secured to a ring 46, adapted to receive hitching attachment of any suitable form of draft means.

In Fig. 2 I have shown means to facilitate folding of the outer sections of the device upon the main sections at times, either for 100 transportation or to permit the passage of traffic on the road occupied by the drag. A derrick 47 is formed of channel iron bent at its center, arranged in upright position transversely of the device, and having end 105 portions of its legs secured pivotally to plates 48 carried by outer marginal portions of the main sections 10, 11 respectively. A brace rod 49 is pivotally connected at one end to the top of the derrick bar 47 and extends rearwardly and downwardly and has its lower end pivotally connected to a plate 50 carried by the inner marginal portion of one of the main drag sections. A winch 51 is carried by each leg of the derrick bar 47 at a suitable distance above the plane of the drag sections and a cable 52 is provided therefor and passes over a pulley block 53 detachably secured to the outer margin of another drag section, such as a wing section 110 33 or 34. The cable 52 then passes over a fixed pulley block 54 carried by the upper part of the derrick, and back to attachment to the first pulley block. It is to be understood that any other suitable arrangement 115 of block and tackle devices may be provided. A ratchet 55 is fixed to the winch 51 and is adapted to be engaged by a pawl 56 pivoted to the derrick bar. This device may be employed to facilitate folding of the outer sec- 120 125 130

tions inwardly and upon the inner sections as desired.

Any number of the sections shown and described, and in any suitable arrangement, 5 may be employed as a drag with which the whole or a half only of a highway may be treated, and simplicity of construction and flexibility in use is coupled with efficient operation and easy manipulation in securing 10 the desired result, especial emphasis being laid upon the repeated treatment of a given surface by and through a single passage of the device.

I claim as my invention—

- 15 1. A road drag, comprising main drag sections pivoted together, supplemental drag sections pivoted to outer margins of said main sections, each of said drag sections having blades alternately inclined in opposite directions; and wing sections pivoted to outer margins of said supplemental sections, each of said wing sections having parallel blades inclined toward the median line of the drag.
- 20 2. A road drag, comprising sections each formed of longitudinal sills, cross bars on and connecting said sills, and a plurality of

blades, mounted on and spaced longitudinally of said sills, said blades being arranged at angles to said sills and cross bars, 30 said sills and cross bars being formed of channel bars, each of said cross bars having at one end a projecting hinge member formed with an eye adapted to engage within a cross bar of an adjacent section and at 35 its opposite end a hinge bolt adapted to engage an eye of a hinge member of an adjacent section.

3. A road drag, comprising main sections pivoted together, supplemental sections pivoted to outer margins of said main sections each of said sections comprising spaced longitudinal sills and cross bars on said sills, and blades spaced apart longitudinally on 40 said sills and arranged in longitudinal and transverse rows and successively inclined in opposite directions, in the longitudinal rows all of the blades in each transverse row being inclined in one direction on one side of the median line of the drag and in the opposite 45 direction on the other side.

Signed by me at Pocahontas, Iowa, this 27th day of February, 1917.

JOHN L. PASCAL.
